(57) **CLAIM**

The ornamental design for a filter, as shown and described.

DESCRIPTION

FIG. 1: Front, top, and right side perspective view

FIG. 2: Rear, bottom, and left side perspective view

FIG. 3: Front view

FIG. 4: Rear view

FIG. 5: Top view

FIG. 6: Bottom view

FIG. 7: Right side view

FIG. 8: Left side view

FIG. 9: Cross-sectional view taken in the direction of line 9-9 at the center of FIG. 3

FIG. 10: Enlarged view of the detail indicated with the number 10 in FIG. 5

FIG. 11: Front, top, and right side perspective view

FIG. 12: Rear, bottom, and left side perspective view

FIG. 13: Front view

FIG. 14: Rear view

FIG. 15: Top view

FIG. 16: Bottom view

FIG. 17: Right side view

FIG. 18: Left side view; and,

FIG. 19: Enlarged view of the detail indicated with the number 19 in FIG. 15.

The broken lines illustrate portions of the filter which form no part of the claimed design.

The dot-dash broken lines illustrate an unclaimed boundary. The gray shading in FIGS. 1, 2, 5 and 6 depicts a filter net, the entirety of which has the appearance illustrated in the enlargement of FIG. 10. The darker gray shading found in the inner most circular portion in FIGS. 11, 12, 15 and 16 depicts a filter net, the entirety of which has the appearance illustrated in the enlargement of FIG. 19.

1 Claim, 19 Drawing Sheets
